UNITED STATES PATENT OFFICE.

JACOB A. WIEBE, OF ADELAIDA, CALIFORNIA.

PLOW.

SPECIFICATION forming part of Letters Patent No. 679,489, dated July 30, 1901.
Application filed April 3, 1901. Serial No. 54,153. (No model.)

To all whom it may concern:

Be it known that I, JACOB A. WIEBE, a citizen of the United States, and a resident of Adelaida, San Luis Obispo county, State of California, have invented certain new and useful Improvements in Plows; and my preferred manner of carrying out the invention is set forth in the following full, clear, and exact description, terminating with claims particularly specifying the novelty.

This invention relates to agricultural implements, and more especially to that class of devices known as "plows;" and the object of the same is to produce a device of this character having in the one machine several points of improvement and advantage which will appear throughout the following specification.

To this end the invention consists in the details of construction hereinafter more fully set forth and claimed, and illustrated in the drawings, wherein—

Figure I is a plan view of this machine complete. Fig. II is an elevation of the right side, with the nearer supporting-wheel removed, the furrow-wheel raised, and the steering-post deflected slightly. Fig. III is a horizontal section through the steering-post. Fig. IV is a detail showing the parts of the steering mechanism. Fig. V is a transverse section through the machine just forward of the main axle and looking to the rear. Fig. VI is a plan view of a turn-table and framework which I may use in this connection. Fig. VII is a section through Fig. VI, showing the operation of the catches for holding the turn-table. Fig. VIII is a perspective detail view of one of the catches shown in Figs. VI and VII.

Referring to said drawings, the numerals 1 designate the main wheels, each of which is mounted on a crank-axle 2, whose inner extremity is journaled for rotation in the main tubular axle 3. The latter supports brackets 4, which in turn sustain a framework 5 of substantially circular shape and whose details of construction form no essential part of the present invention. However, I preferably arrange a plus-shaped cross 6 on the top of this framework and extend one of the arms forward, as at 7, while two of the side arms 8 are carried obliquely forward,

and all three arms are bolted to the head-block 9, in which moves the steering-post. Moving vertically through the head is a rack-bar 10, whose teeth engage with a pinion 11, mounted on a shaft 12, which carries a gear 13, meshing with the internal teeth of a basket-gear 14, which turns on a stub-shaft 15 in the head. 16 is a lever pivoted on the stub-shaft and having a thumb-lever 17 engaging exterior teeth on the basket-gear 14, and by manipulation of this lever it will be seen that the rack-bar can be raised or lowered. A latch 18 is moved through a lug 19 in the head by means of a cam or handle 20 pivoted thereto, and the tip of this latch may enter between the external teeth of the basket-gear 14 when it is desired to lock the rack-bar at any given height. At its extremity 21 said rack-bar carries eyes 21, in which is journaled the steering-post 22, whose lower end is bent obliquely downward and outward, as at 23, and carries the sharp-edged steering-wheel 24. To the upper end of this post is attached a laterally-projecting arm 25, which is connected by a rod 26 with a hand-lever 27, moving over a segment 28 and standing adjacent the driver's seat 29. By manipulating this lever the steering-post and with it the guiding-wheel may be swung from side to side, and as its sharp edge embeds itself in the earth before the furrow is formed it is evident that the plow can be steered as desired. The team is obviously attached there-to forward of the steering-head, and it will be guided by the driver as may be necessary. The steering can occur whether the steering-wheel is caused to embed the earth to a considerable extent or less.

At the rear end of the machine is a sharp-edged wheel 30, intended to embed the earth and travel in the furrow, and when it does so it will be clear that it is impossible to change the course of the machine. In order to steer the machine, the furrow-wheel is mounted in a hanger 31, pivoted at 32 to the framework, and 33 is a hand-lever moving over the toothed segment 34 and connected by a rod 35 with a fork 36, attached to the hanger 31, so that by manipulating this hand-lever the furrow-wheel may be raised and lowered and held at any desired position, and the steering is then done by the wheel 24. Each main wheel 1

has attached rigidly to its crank-shaft a hand-lever 37, moving over a toothed rack-bar 38 and standing adjacent the driver's seat, and the use of these levers, as is well known in the art, is to turn the crank-shafts so that the flat-faced supporting-wheels 1, which rest upon the surface of the earth, will raise or lower the entire machine to such an extent as to embed the plow to the desired degree in the ground or raise the same entirely out of the ground when the machine has to be transported from place to place. In the present instance I have shown three disk-shaped shares 40, each journaled on and supported by a standard 41, which in turn depends from and is carried by a turn-table 42, that is mounted loosely for rotation within the circular guideway 43, formed in the main framework. The axes of these disks stand in a single plane, and according as that plane is swung from one side of the line of draft to the other so will the furrow be thrown up to one side of the machine or the other. Such movement may readily be accomplished by raising the furrow-wheel at the back, depressing the steering-wheel at the front, and then turning the steering-post and guiding the team so as to swing the front of the machine to the right or to the left, the disks mean-while being permitted to remain embedded in the ground. When it is desired simply to turn corners or to reverse the machine without changing the direction of the furrow, the levers 37 are manipulated so as to raise the framework and lift the plow out of the ground, and thereafter the steering of the machine will turn it, while not swinging the turn-table within the guideway.

In Figs. VI and VII, I show one means of constructing the turn-table and locking it at one of two positions within the guideway 43. Here the turn-table 42 is plus-shaped like the part 6 of the framework, and the latter carries the guideway 43, in which move the tips of the crossed beams forming the turn-table, thus obviating the necessity for a pivot-belt. In the present instance one of said crossed beams is narrow and two catches are provided which are duplicates of each other. Each catch comprises an arm or two arms 44, pivoted at 45 upon the top of the guideway and having at their outer ends a cross-piece 46, which at its transverse extremities is bent downward and then outward and obliquely upward into hooks 47, whereby the beam approaching from either direction will ride under the nearest hook and into the space between the hooks, when the catch will fall and hold the turn-table locked. 48 is an arch standing over this catch, and 49 is a bell-crank lever pivoted in the arch, with one arm connected by a rod 50 with the catch. Through the other and upper arm of this lever passes a rod 51, having a head 52 at its outer end, while its inner end is connected with one arm of the bell-crank lever 55, pivoted at 56 on the framework and having a

footpiece 57 in its other arm. As before stated, there are two of these catches, and when the operator depresses the footpiece 70 both catches are raised, thus freeing the turn-table, no matter which catch previously held it. By properly turning the machine the axial line of the disks is changed, as above explained, and, the driver's foot being removed 75 and the catches dropped as soon as the turn-table begins to turn, when the proper point has been reached the narrow beam is automatically engaged by the other catch in a manner which will be clear. The headed rod 51 80 obviously slides through the eye in the upper arm of the bell-crank lever 49 when either catch rises to automatically engage the narrow beam of the turn-table. I do not limit myself to this specific construction of fastening means for the turn-table, as others might be employed to advantage. In fact, I desire not to be limited to the exact construction of any part of this machine further than as set forth in the claims below. 90

In use the team is attached and the driver takes his seat. By throwing the main wheels down and setting the guiding-wheel properly the machine can be driven to the place where the work is to occur without having the disks 95 enter the ground. Then by raising the main wheels the entire framework and disks are permitted to descend. As soon as the machine starts and the furrow is formed the guiding-wheel is raised and the furrow-wheel at the rear is dropped into the furrow, so as to make the latter straight. In sidehill-plowing the independent setting of the main wheels will be found of advantage, for a reason which will be clear to those skilled in the art. The 105 operation of turning corners or of shifting the angle of the axial line of the disks to the line of movement has been described above. The parts may be of any desired sizes, shapes, proportions, and materials, though the whole is 110 preferably of metal.

In Fig. I, I have shown the turn-table in dotted lines beneath the flooring of the framework, and the flooring is broken away at one point to illustrate a stop 444, against which 115 one arm of the plus-shaped turn-table strikes at one extremity of its rotary movement. A similar stop is located at the other side of the framework, against which the opposite end of this (here the wider) arm 42 of the turn-table 120 strikes when it is turned to the other extremity of its movement. This arrangement is obviously much simpler than the one illustrated on Sheet 3, which involves the use of catches and a footpiece, and the stops serve 125 the purpose nearly or fully of the catches, because they prevent the turn-table from turning farther than desired.

Having thus described my invention, what I claim is—

1. In a plow, the combination with the framework carrying the share, and a crank-axle having two supporting-wheels for said framework; of a steering-wheel at the front

- end of the framework, a furrow-wheel at the rear end of the framework, and means for raising one of these wheels, all substantially as described.
5. 2. In a plow, the combination with the framework carrying a share, a crank-axle having two supporting-wheels, and means for setting the crank thereof with relation to the framework; of a furrow-wheel at the rear end of the framework, steering mechanism at the front end of the framework, and means for raising this mechanism off the ground, all substantially as described.
10. 3. In a plow, the combination with the framework carrying a share, a crank-axle having two supporting-wheels, and means for setting the axle thereof with relation to the framework; of steering mechanism at the front end of the framework, means for raising this mechanism off the ground, a furrow-wheel at the rear end of the framework, and means for raising it out of the furrow, all substantially as described.
15. 4. In a plow, the combination with the framework, its support, and the share; of a head at the front end of the framework, a steering-post journaled therein, a wheel mounted at its lower end, an arm at the upper end of this post, a hand-lever connected with this arm and moving over a toothed rack, a rack-bar connected with the extremities of the post and moving through said head, a pinion engaging this rack-bar, a gear connected with said pinion, a basket-gear meshing with said other gear, a hand-lever for manipulating this basket-gear, and a latch for holding it against rotation, as and for the purpose set forth.
20. 5. In a plow, the combination with the framework having a circular guideway, two independent crank-shafts adjustable in the framework, and supporting-wheels thereon; of a turn-table mounted rotatably within the guideway, standards depending from the turn-table, and disk shares carried by the standards, as and for the purpose set forth.
25. 6. In a plow, the combination with the framework having a circular guideway, a crank-shaft adjustable in the framework, and supporting-wheels thereon; of a turn-table mounted rotatably within the guideway, standards depending from the turn-table, disk shares carried by the standards, and means for adjustably holding the turn-table in the guideway with the plane of the disk axes at different angles to the line of draft, substantially as herein specified.
30. 7. In a plow, the combination with the framework, supporting-wheels therefor, a trailing furrow-wheel, and means for raising this wheel when desired; of a turn-table rotatable within the framework, a standard depending therefrom, and a disk share journaled on said standard, the whole operating substantially as described.
35. 8. In a plow, the combination with the framework, supporting-wheels therefor, and a trailing furrow-wheel; of a turn-table rotatable within the framework, a standard depending therefrom, a disk share journaled on said standard, and means for locking said turn-table in a number of positions, as and for the purpose set forth.
40. 9. In a plow, the combination with the framework having a circular guideway, and means for supporting and steering the framework; of a turn-table rotatably mounted in said guideway, standards depending from the turn-table, disk shares carried by the standards, a foot-lever on the framework, and a plurality of catches on the guideway adapted to automatically lock the turn-table in a number of positions and to be simultaneously unlocked by movement of the foot-lever, substantially as described.
45. 10. In a plow, the combination with the framework having a circular guideway, and means for supporting and steering the framework; of a turn-table comprising beams connected in plus shape and having their tips rotating in said guideway, standards depending from said turn-table, disk shares carried by the standards, a plurality of catches pivotally mounted on the guideway and each having arms with inclined outer ends adapted to automatically engage one of said beams, and means for simultaneously lifting all the catches, substantially as described.
50. 11. In a plow, the combination with the framework having a circular guideway, and means for supporting and steering the framework; of a turn-table comprising beams connected in plus shape and having their tips rotating in said guideway, one of said beams being narrower than the other, a plurality of catches pivotally mounted on the guideway and each comprising a cross-piece bent at its extremities downward and then outward and obliquely upward into hooks spaced so as to automatically engage the narrower beam but not the wider, and means for raising these cross-pieces, substantially as described.
55. 12. In a plow, the combination with the framework having a circular guideway, and means for supporting and steering the framework; of a turn-table comprising crossed beams having their tips rotatable in said guideway, a plurality of catches each comprising a cross-piece pivotally supported on the guideway and having hooks at its extremities, an arch standing over the catch, a lever pivoted in the arch and connected with the catch, and means for swinging all the levers simultaneously, as and for the purpose set forth.
60. 13. In a plow, the combination with the main framework having a plus-shaped cross on its top with one arm extending forward, a circular guideway carried by this cross, two side arms carried obliquely forward from the guideway, a head-block at the front end of

all these arms, steering mechanism therein, and a support for the framework; of a turn-table comprising beams in plus shape whose extremities move rotatably in said guideway, catches mounted on the latter for holding the turn-table in various positions, a single lever on the cross of the framework connected with all the catches, standards depending from the turn-table, and disk shares mounted in the

standards, all as and for the purpose herein-
before set forth.

In testimony whereof I have hereunto sub-
scribed my signature this the 22d day of
March, A. D. 1901.

JACOB A. WIEBE.
